STAMP CONTAINER

Filed Nov. 5, 1921

UNITED STATES PATENT OFFICE.

LUCILLE COX, OF CHICAGO, ILLINOIS.

STAMP CONTAINER.

Application filed November 5, 1921. Serial No. 513,063.

To all whom it may concern:

Be it known that I, LUCILLE Cox, a citizen of the United States, residing at Chicago, in the county of Cook and State of Illinois, have invented a new and useful Stamp Container, of which the following is a specification.

This invention relates to containers for pocket and personal use, the primary object 10 of the invention being to provide a container especially designed for holding stamps or the like.

Another object of the invention is to provide a container including opposed hinged 15 sections, the sections being connected so that the flexibility of the metal of which the container is formed, will cause the sections to be held in their closed positions, but permit the sections to be moved with respect to each 20 other, to open the container.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view of a container constructed in accordance with the 30 present invention.

Figure 2 is a side elevational view of the same.

Figure 3 is an end elevational view of the container.

Figure 4 is an elevational view disclosing the cover portion thereof as moved to a semi-open position.

Figure 5 is an enlarged sectional view through one end of the container, and

Figure 6 is a side elevational view of the container disclosing the cover thereof in a semi-open position.

Referring to the drawing in detail, the container embodies opposed sections 5 and 6, 50 the section 5 constituting the body portion

of the container, while the section 6 constitutes the cover thereof.

The body portion 5 is formed with upwardly extending flanges 7 forming the side walls of the body portion, and an upwardly 55 extending flange 8, forming one of the end walls thereof. Formed integral with the end wall 8, is a tongue 9 to which the cover 6 is pivotally connected as at 10.

An ear 11 is formed integral with the 60 opposite end of the body portion 5 and provides means to be gripped by the person using the container, to slide the cover 6 to an open position. The body portion 5 is cut away as at 12 to provide a clearance for 65 the flange 13 which is formed integral with the cover 6 and which depends therefrom.

Formed integral with the cover section 6 is an extension 14 which is apertured as at 15 to permit the container to be secured to 70 a key ring, watch chain or the like to insure against losing the same.

In the use of the device, it is contemplated that stamps or an identification slip may be held in the container, and that when it is 75 desired to open the container, the operator places his fingers on the ear 11 of the body portion 5, and extension 14 of the cover 6, gripping the same. With the operator's hands in this position, the extension 14 is 80 forced downwardly, causing the opposite end of the cover 6 to be tilted upwardly. It follows that a slight twisting of the cover will cause the flange 13 to ride over the side wall 85 of the body portion.

When the container is to be closed, the cover is swung in the opposite direction, the flange 13 riding over the side wall of the body portion, contacting therewith, where the same drops into the cut away portion 12 90 and prevents accidental movement of one section with respect to the other.

Having thus described the invention, what is claimed as new is:—

In a container, opposed sections pivotally 95 connected, one of said sections having a tongue disposed at one end thereof and located intermediate the side edges thereof and having a cut out portion formed at its opposite end between the side walls thereof, 100

the opposite section having a flange depending from the under surface thereof, said flange being of a width to fit within the cut out portion of the opposed section, the ends 5 of said flange adapted to contact with the end walls of the cut out portion to lock the sections together.

In testimony that I claim the foregoing as my own, I have hereto affixed my signature in the presence of two witnesses.

LUCILLE COX.
